UNITED STATES PATENT OFFICE

2,351,420

FURNACE CONTROL SYSTEM

Donald E. Garr and George E. Shaad, Schenectady, N. Y., assignors to General Electric Company, a corporation of New York

Application March 27, 1943, Serial No. 480,824

6 Claims. (Cl. 314—75)

Our invention relates to furnace control systems, more particularly to control systems for electric electrode furnaces, and has for its object a sensitive and dependable control system which may be operated either as a fully automatic or as a manually controlled system.

In carrying out our invention in one form we raise and lower the electrode by means of a motor which is supplied with current from a generator whose voltage may be varied with precision and great amplification in response to furnace conditions thereby to control automatically the raising and lowering of the electrode during the operation of the furnace.

More particularly, we control the generator by controlling its main field winding in accordance with the difference between two voltages, one of which is responsive to the current in the electrode and the other of which is the voltage across the arc between the electrode and the furnace charge. Any difference in these voltages is impressed on the generator field winding thereby to give a generator voltage whose value is dependent upon the value of this difference in voltage, and whose direction is dependent upon the direction of this differential voltage. The motor raising and lowering the electrode thus operates at a speed dependent upon the generator voltage and in a direction dependent upon the direction of the generator voltage thereby to raise or lower the electrode and make the necessary adjustment to maintain a uniform current in the electrode.

More specifically, we provide a generator for the electrode motor of the armature reaction type whose voltage responds very quickly and with very high amplification to any change in its field excitation, preferably of the type described and claimed in Patent No. 2,227,992, issued to Ernst F. W. Alexanderson and Martin A. Edwards on January 7, 1941.

We also provide two manually operated control switches for selecting between manual and automatic or partially automatic operation, one switch being a master switch and selecting between manual or automatic operation for all of the electrodes, such as for all three electrodes in a three-phase furnace, and a manual switch being provided for each electrode for controlling separately the generator for that electrode thereby to raise or lower the electrode manually.

For a more complete understanding of our invention, reference should be had to the accompanying drawing in which the single figure is a diagrammatic view of an arc furnace control system embodying our invention.

Referring to the drawing, we have shown our invention in one form as applied to the raising and lowering of an electrode 10 in an arc furnace with relation to a metal charge 11 contained in

a suitable crucible 12. The electrode 10 and also the other two electrodes of the three-phase furnace shown are raised and lowered each by a suitable direct current motor 13 which is suitably connected to the electrode. As shown, the shaft 14 of the motor is connected preferably through suitable speed reducing gearing to a sheave 15 over which passes a cable 16 connected to the electrode, the other end of the cable being provided with a counterweight 17.

Direct current is supplied to the motor 13 by means of a special high amplification generator 18 of the armature reaction type. This generator has a set of output brushes 19 and 20 which are connected to the terminals of the motor 13 and a second pair of brushes 21 and 22 which are permanently short-circuited through a conductor 23 and which are in quadrature relation with the current supply brushes 19 and 20. Also, the generator 18 is provided with a series compensating winding 24 which substantially neutralizes the armature reaction of the generator along the current supply brushes 19 and 20, together with a main field excitation winding 25 which provides magnetic excitation along the secondary axis of the brushes 19 and 20. The sensitivity of control of the voltage by variation of the excitation of the winding 25 is increased by means of the field winding 24 which supplies excitation in the same direction as the field 25 but proportional to the current supplied to the motor 13. With this arrangement the control field winding 25 is required to supply only a relatively small excitation and, consequently, it has both a low resistance and a low inductance which provide for very rapid changes of current in it.

The field winding 25 is connected for energization across two voltages in opposition to each other so as to be energized in response to the difference in these voltages. One of these voltages is derived from a current transformer 26 connected in the electric supply circuit for the electrode 10 and is substantially proportional to the current in the electrode. The other voltage 45 is derived from a secondary winding 27 of a transformer whose primary winding 28 is connected across the electrode and the charge 11 and is substantially proportional to the arc voltage. These voltages are rectified for the field winding 50 25 by means of two-way copper oxide rectifier means 29 and 30 respectively. Also, to provide for adjustment, the voltage of the rectifier 30 is applied to a resistance 31 which, together with the rectifier 29, is connected in circuit with the field winding 25.

From its left-hand terminal the circuit of the coil 25 leads through a normally closed switch 32 forming a part of an individual electrode controller 33, a normally closed switch 34 controlled 55 by a master controller 35, the rectifier 29, an

adjusted portion of the resistance 31, an adjusted portion of a regulating resistance 36, a normally closed switch 37 operated with the switch 34, a normally closed switch 38 operated by the controller 33 and conductor 39 through the normally closed "raise" and "lower" limit switches 40 and 41, and conductor 42 back to the right-hand side of the winding 25.

When the electrode 10 is raised out of contact with the charge 11 and no arc is established, as in the starting of the furnace, no current, of course, flows in the electrode and consequently the entire voltage selected from the resistance 31 is applied to the generator field winding 25. This voltage energizes the field winding in a direction to cause the motor to lower the electrode. This initial lowering operation, however, is preferably at a relatively slow speed, and to effect this the resistance 36 is provided which is adjusted to give the desired slow lowering speed for striking the arc.

When the electrode 10 is lowered far enough to come in contact with the charge, the primary winding 28 is thus short-circuited and the voltage across the rectifier 29 is reduced to zero. However, a large surge of current occurs at this time in the electrode circuit in response to which a voltage is impressed on the rectifier 29 for reversal of the excitation of the winding 25 and reversal of the electrode motor. Immediately the coil 43 connected across the rectifier 29 in series with a current limiting resistance 44 is energized and closes the switch 45 thereby short-circuiting the resistance 36 for maximum energization of the field winding 25 for quick raising or recovery of the electrode to an arcing position, and for high speed adjustment of the electrode during the operation of the furnace. The electrode is raised until the electrode current is of such value that the voltage output of the rectifier 29 is substantially equal to the voltage from the resistance 31 in series with it. Under these conditions, since the two voltages oppose each other, no current flows in the generator field and the motor is consequently deenergized so that the electrode is held in that position.

The relay switch 45 remains closed as long as current flows in the electrode circuit. If for any reason the arc is extinguished, the switch 45 immediately opens and the electrode is lowered at a slow speed again to reestablish the arc.

The position of the electrode corresponding to the setting of the resistance 31 is now held automatically. If the furnace current decreases, the voltage from the rectifier 29 likewise decreases and the field winding 25 is energized in a direction to lower the electrode until balance is again restored. Conversely, if the furnace current increases above the predetermined value corresponding to the adjustment of the resistance 31, the voltage from the rectifier 29 likewise increases and the field winding 25 is energized in the opposite direction to raise the electrode until balance is again restored.

A variable current adjusting resistance 46 is connected across the current transformer 26 by means of which the control may be adjusted for ranges beyond the normal range of the resistance 31.

A blocking rectifier 47 is provided across the lowering limit switch 41. This rectifier passes current only in a direction to raise the electrode and provides for the raising of the electrode in the event that the electrode is driven to its lower limit and opens the limit switch 41. Ordinarily

the electrode will not be raised to its upper limit and open the limit switch 40 but if this should occur, the control must be transferred to manual operation, as hereinafter described, in order to lower the electrode.

For the purpose of increasing the inherent anti-hunt characteristics of the apparatus, an additional field winding 48 is provided for the generator, this field winding being connected directly across the armature of the generator. Its polarity is such that it always opposes the main field winding 25 with the result that it gives an anticipatory action. The strength of the anti-hunt field from the winding 48, and hence sensitivity of the generator, may be varied by varying the strength of energization of the winding 48 by means of a variable resistor 49 in series with the winding 48. A blocking rectifier 50 is provided across a section of the resistance 49 in a direction to pass current and short out a portion of the resistance 49 when the electrode is being lowered. This provides a separate adjustment to reduce the lowering speed to a much lower value than the raising speed thereby to prevent breakage of the electrode, such as when melting heavy scrap metal.

An iron core saturable reactor 51 is connected across the current transformer 26. This reactor saturates in the event of heavy current surges, such as are commonly encountered at the beginning of the furnace operation when the arc is made and broken rapidly before the furnace current reaches a steady state. The saturation of the reactor 51 limits to a safe value the voltage that can be impressed on the rectifier 29.

It will be understood that a regulator for the three-phase furnace shown has for each phase duplicate regulating equipment as thus far described.

For the manual control of the furnace the individual controller 33 and the master controller 35 are provided, there being an individual controller 33 for each electrode and a single master controller 35 for all two or three electrodes of the furnace. During automatic operation the handle 52 of the master controller is pulled out whereby its switch 53 is closed and the handle is thereby locked against turning so that its switches 54 and 55 are locked open. The switch 53 energizes a coil 56 which maintains closed the switches 34 and 37 and also closes a third switch 57 whose function is to make effective the individual controller 33. Also, similar switches (not shown) actuated by coils in parallel with the coil 56 are closed for the controls on each of the other electrodes of the furnace.

Also during automatic operation, the handle 58 of the individual controller 33 is pulled out and thereby locked against turning whereby the switches 32 and 38 are closed for automatic operation.

If it is desired now to control one electrode manually, leaving the other electrodes on automatic operation, this may be done with the individual controller 33 for that electrode. The handle 58 is pushed in whereby the switches 32 and 38 are opened and the field winding 25 thus disconnected from the automatic control apparatus. Current for energization of the field winding 25 is now supplied from a resistance 59 connected across direct current supply lines 60 and 61. Also when the handle 58 is pushed in, the switch 61a is closed and remains closed when the handle is turned. Turning the switch 33 clockwise to a "raise" position closes the switch

62, and also a switch 63, whereby the field winding is connected across the points 64 and 65 of the resistance 59 and is energized in a direction to raise the electrode. This circuit leads from the left-hand side of the field through the switch 57 and switch 62, both of which are closed, to the point 64, thence through the resistance to the point 65 and through the switch 61a, conductor 39, limit switch 40, conductor 65a, switch 63, and conductor 42 back to the right-hand side of the field winding. It will be noted that the switch 63 by-passes the lowering limit switch 41. To lower the electrode, the controller 33 is turned counterclockwise to a "lower" position whereby the switches 66 and 67 are closed, and the switch 61a will be likewise closed. This connects the field winding across the points 65 and 68 on the resistance, the circuit leading from the left-hand side of the field winding through the switch 57, the switch 67, to the point 68, through the resistance to point 65, switch 61a, conductor 39, switch 66, conductor 65a, limit switch 41, and conductor 42 back to the right-hand side of the field winding.

In the event that it is desired to raise or lower all of the electrodes manually as a group, the master switch 35 only is used. The handles 58 of the individual controllers may at this time be in either their automatic or manual operating positions. The handle 52 of the master controller is pushed in whereby the switch 53 is opened and the field winding of each motor isolated from its control by the opening of the corresponding switches 34 and 37 and the switch 57. Turning the handle 52 clockwise to the "raise" position closes the switch 54 whereby the "raise" coil 69 is energized, together with similar parallel connected "raise" coils (not shown) for the other electrodes. This coil 69 closes the switches 70 and 71 whereby each field winding is connected across the points 65 and 72 of resistance 59 for energization in a "raise" direction.

To lower the electrodes, the master switch is turned counterclockwise to the "lower" position whereby the switch 55 is closed and the coil 73, together with other parallel connected similar coils (not shown), are energized. This closes the switches 74 and 75 whereby the field winding is connected for reverse energization across the points 65 and 76 of the resistor. It will be noted that these connections give higher voltages for the field winding across the resistor than are obtained for individual electrode control whereby higher speeds are provided. If desired, a separate field winding can be provided for the generator for use during manual control, the field winding 25 being used as described during automatic control. Thus the field excitation means may consist of one or more field windings.

Ordinarily in the operation of the furnace, several voltages are used as desired in the melting of a charge. As shown, the primary winding 77 of the transformer supplying energy to the electrode 10 is provided with three taps which may be selected by a rotatable arm 78 to give three different voltages. When the voltages change, however, it is necessary to adjust the value of the voltage applied by the secondary winding 27 to the rectifier 30 so that the voltage actually applied to the rectifier remains unchanged. This is done by correspondingly changing taps on a regulating resistance 79 in circuit with the rectifier. Thus we have shown a short-circuiting switch arm 80 mechanically 75

connected by a link 81 to the transformer switch arm 78 so that a change in transformer voltage makes simultaneously a corresponding off setting change in the resistor 79 and the voltage applied to the rectifier remains unchanged.

An advantage in using the arc voltage as a bias voltage or as a standard value against which the current is compared is obtained in the control of the furnace under conditions causing very low arc voltage. For example, when a large piece of metal falls against the electrode and short-circuits the arc, the current in the electrode circuit rises to a very high value and the arc voltage drops to practically zero. Under these conditions, the greatly increased current energizes the field winding 25 so as to cause raising of the electrode and, in addition, this effect is still further increased by the greatly increased differential control voltage caused by the drop in arc voltage. In the case of a three-phase furnace, this short-circuiting of one arc causes an increase in the current in the other two electrodes, but with an increase in their arc voltages so that the increase in current is substantially offset by the increases in arc voltages, and very little regulation of these two electrodes takes place.

It will be understood that any suitable construction can be used for the manually operated switches 33 and 35. As shown diagrammatically, the switch 33 is provided with an operating shaft 82 on which is splined a shaft 83 carrying the movable contacts of the switches 62, 63, 66 and 67. Thus when the handle is in its pushed in or lowered position, as seen in the drawing, it may be turned from the mid position shown in a clockwise direction looking down on the handle to close the switches 62 and 63, or turned in a counterclockwise direction from this mid position 40 to close the switches 66 and 67. The shaft 82 carries a disc 84 having a notch 85 which registers with a stationary stop 86 when the shaft is in the mid position shown so that the shaft can be pulled out or upward, the sides of the notch embracing the stop 86, thereby to close the switches 32 and 38. When the shaft is thus pulled out, the stop 86 prevents turning of the shaft and thereby prevents closure of the switches 62, 63 or 66, 67. Also carried by the shaft is a second disc 87 which when the shaft is pushed in or downward, as shown, closes and holds closed for all positions of the shaft the switch 61a. This switch is biased open as by a suitable spring and opens when the shaft and disc 87 are moved upward.

The master switch 52 is shown diagrammatically in a similar manner, this switch having an outer sleeve 88 splined on its shaft and operating the switches 54 and 55. It also is provided with a lock (not shown) similar to 84, 85 and 86 of the switch 33 assuring that the switches 54 and 55 are open when the switch is raised.

While we have shown a particular embodiment of our invention, it will be understood, of course, that we do not wish to be limited thereto since many modifications may be made, and we therefore contemplate by the appended claims to cover any such modifications as fall within the true spirit and scope of our invention.

70 What we claim as new and desire to secure by Letters Patent of the United States is:

1. A control system for a furnace provided with an electrode comprising a transformer for supplying current to the electrode, a motor for moving the electrode thereby to vary the current

in the electrode and the voltage between the electrode and a charge, a generator for supplying current to said motor to operate said motor, field excitation means for said generator, means differentially responsive to the current in the electrode and the voltage between the electrode and a charge for energizing said field excitation means thereby to cause said motor to move the electrode and maintain a predetermined current in the electrode, means for varying the voltage supplied by said transformer to the electrode, means for varying the response of said differential means to said voltage, and means for simultaneously actuating said two varying means to maintain a predetermined response of said differential means to said voltage independently of the value of said voltage.

2. A control system for a furnace provided with an electrode comprising a motor for moving the electrode thereby to vary the current in the electrode and the voltage between the electrode and a charge, a generator for supplying current to said motor to operate said motor, field excitation means for said generator, means differentially responsive to the current in the electrode and the voltage between the electrode and a charge for energizing said field excitation means thereby to cause said motor to move the electrode and maintain a predetermined current in the electrode, and means responsive to the surge of current in the electrode when the electrode is moved into engagement with the charge for increasing the energization of said field excitation means for increased speed of movement of the electrode during subsequent adjustment of the electrode to maintain said predetermined current.

3. A control system for an arc furnace comprising a motor for raising and lowering the electrode thereby to vary the current in the electrode and the voltage between the electrode and a charge, current responsive means for producing a first voltage responsive to the current in the electrode, voltage responsive means for supplying a second voltage responsive to the voltage between the electrode and a charge, differential voltage supply means for rectifying and comparing said voltages and for supplying a third voltage responsive to the difference between said first and second voltages, a generator for supplying current to said motor to operate said motor, field excitation means for said generator, a resistance, connections for connecting said differential voltage supply means to said field excitation means in series with said resistance thereby to cause said motor to raise and lower said electrode in dependence upon the polarity of said third voltage and maintain a predetermined current in said electrode, and means responsive to said first voltage for short-circuiting said resistance when the electrode touches the charge thereby to increase the energization of said field excitation means and the speed of operation of said electrode.

4. A control system for a furnace provided with an electrode comprising supply means for supplying current to an electrode, a motor for raising and lowering the electrode thereby to vary the current in the electrode and the voltage between the electrode and a charge, an armature reaction type generator for supporting current to said motor to operate said motor, field excitation means for said generator, means differentially responsive to the current in said electrode and the

voltage between the electrode and a charge for energizing said field winding thereby to cause said motor to raise or lower said electrode and maintain a predetermined current in said electrode, 5 an anti-hunt field winding for said generator connected to said generator, a resistance in circuit with said field winding, and a blocking rectifier connected across at least a portion of said resistance so as to short-circuit said portion of said resistance when the electrode is being lowered thereby to reduce the electrode lowering speed.

5. A control system for an arc furnace comprising a transformer for supplying current to an electrode, a motor for raising and lowering the electrode thereby to vary the current in said electrode and a charge, a generator for supplying current to said motor to operate said motor, a field for said generator, means differentially responsive to the current in said electrode and the voltage between the electrode and a charge for energizing said field winding thereby to cause said motor to raise or lower said electrode and maintain a predetermined current in said electrode, and means for varying concurrently the voltage supplied by said transformer and the response of said differential means to said voltage in offsetting relation to each other thereby to maintain a predetermined response of said differential means to said voltage independently of the value of said voltage.

6. A control system for an arc furnace provided with a plurality of electrodes supplied with alternating current comprising a motor for raising and lowering each electrode thereby to vary the current in said electrode and the voltage between the electrode and a charge, current responsive means associated with each electrode for producing a first alternating voltage responsive to the current in the electrode, voltage responsive means for each electrode for supplying a second alternating voltage responsive to the voltage between the electrode and the charge, 35 differential voltage supply means for each electrode for rectifying and comparing said voltages and for supplying a direct voltage responsive to the difference between said first and second voltages, a generator for supplying current to each of said motors, field excitation means for each of said generators, connections for supplying a constant direct voltage for said field excitation means, a manually operated control device for each of said electrodes movable to one position to connect the field excitation means of the corresponding generator to said differential voltage supply means, and movable to other positions to connect said field excitation means to said direct voltage supply connections so as to control the 40 direction of energization of said field excitation means for manual control of the corresponding electrode, and a second manually operated control device movable to one position to establish connections for each of said field excitation means with its differential voltage supply means and movable to other positions to connect each of said field excitation means to said direct voltage supply connections so as to control the direction of energization of all of said field excitation means for concurrent manual control of all 45 of said electrodes.
